REMOTE CONTROL SYSTEM

Paul H. Crago, Wilkinsburg, Pa., assignor to The Union Switch & Signal Company, Swissvale, Pa., a corporation of Pennsylvania

Application July 10, 1941, Serial No. 401,753

4 Claims. (Cl. 246—219)

My invention relates to a remote control system, and more particularly to a remote control system for railways.

In remote control systems for railways continuous control and indication of switches, signals and other traffic governing units are provided. The control station or office and the switches and signals are usually relatively far apart and for economy of apparatus and circuits it is desirable that the control and indication influences for the different switches and signals be transmitted in each case over a single line circuit. The track layout of an interlocking is in many instances unbalanced as to the number of switches and signals. When such an interlocking is controlled from a remote office through the medium of a remote control system, extra line circuits and apparatus may be required because of the unbalanced layout and such extra circuits and apparatus add to the initial cost and to the upkeep of the system.

In view of the above circumstances in remote control systems for railways, a feature of my invention is the provision of a remote control system for railways incorporating novel and improved means wherewith each traffic governing unit of an interlocking is continuously controlled and indicated over a control line circuit including a control line wire and a common line wire, the common line wire serving as one side of several such control circuits. A traffic governing unit as referred to above, may consist of a single switch or of one signal, or of two or more related switches that can be operated together, or of two or more related signals that can be selectively controlled.

Another feature of my invention is the provision in a remote control system for railways of novel and improved apparatus and circuits wherewith no critical time values in the operation of any part of the apparatus and circuits are involved.

Still another feature of my invention is the provision of a remote control system for railways incorporating novel apparatus by which the system is made flexible for application without extra line circuits to an interlocking having an unbalanced layout of switches and signals.

Again, a feature of my invention is the provision of novel means for remote control systems wherewith not only the normal and reverse positions of a switch are indicated but indications of "switch in transit" and "switch locked" are provided as well as an indication of a train in the vicinity of such switch.

Other features, advantages and objects of my invention will appear as the specification progresses.

The above features and advantages of my invention are obtained by providing each traffic governing unit of an interlocking with a control line circuit which extends between the controlling office and a station located adjacent the interlocking, and which line circuit terminates in four branch circuits at each of the two locations. That is, in the remote control of an interlocking, each traffic governing unit which may consist of a single switch or of one signal, or of a pair of related switches or of two or more related signals, is provided with a control line circuit, one wire of which serves as a common wire for several of such circuits. In each such control line circuit, two of the four branch circuits at the office and at the station function in the receiving of current, and the other two branch circuits at the office and at the station function in the sending of current.

Each such receiving branch circuit preferably includes an asymmetric unit and a magnetically biased neutral relay in series. These asymmetric units may be of any one of several different types and may be, for example, copper oxide rectifier elements. At the office and at the station the two asymmetric units of the two receiving branch circuits of a control circuit are disposed reverse to each other so that one receiving circuit is conditioned to pass current of one polarity only and the other receiving circuit is conditioned to pass current of the other polarity only. The magnetically biased neutral relays are of the type that respond to current of one polarity only. That is, each relay is biased magnetically as well as by gravity so that its armature is released to engage back contacts when the relay is deenergized, is held at its released position when the relay is energized by current of one polarity, and is picked up when the relay is energized by current of the opposite polarity. Each biased neutral relay is disposed in the respective receiving branch circuit so as to be picked up by current of the polarity passed by the asymmetric unit of the same receiving circuit.

At the office and at the station each of the two sending branch circuits of each control circuit includes an asymmetric unit, the two asymmetric units being disposed reverse to each other. Consequently, the current passed to a control line circuit by a particular one of the associated sending branch circuits of either location is of the polarity that is passed by a particular one of the

receiving branch circuits of the same control circuit at the other location.

At the office a source of alternating current is connected to each of these control line circuits through the sending branch circuits of the respective control circuit, the sending branch circuits being selectively closed over contacts of an associated manually controlled means. The arrangement is such that at one position of the manually controlled means, the sending branch circuit of the associated control circuit effective to pass the half cycles of one relative polarity of the alternating current is closed and the other sending branch circuit is open, and at a second position of the manually controlled means, the sending branch circuit effective to pass the half cycle of the other relative polarity of the alternating current is closed and the other one is open. Furthermore, at the office, the receiving branch circuit of a control line circuit effective to pass current of said one relative polarity is closed at the first position of the associated manually controlled means and the one effective to pass current of said other relative polarity is opened, and at the second position of the manually controlled means this condition of the receiving branch circuits is reversed. It follows that a receiving branch circuit at the office cannot be energized by current supplied by the office current source. At the office the biased neutral relays associated with each control line circuit are used to govern an associated indication means, such indication means being controlled to a first or a second condition according to which one of the two relays is picked up.

At the station the magnetically biased neutral relays of the receiving branch circuits of each control circuit govern the operating circuits of an associated traffic governing unit, such traffic governing unit being operated to a first or a second position according to which one of the two relays is picked up. A source of alternating current is also provided at the station. Contacts governed by each traffic governing unit selectively connect the station current source to the two sending branch circuits of the associated control line circuit according to the first or second position of the traffic governing unit. Also at the station the receiving branch circuits of each control circuit are interlocked so that only one receiving branch circuit can be closed at a time.

The relationship between the contacts of the manually controlled means of a control line circuit and the contacts governed by the associated traffic governing unit is such that when half cycles of one relative polarity of the alternating current source at the office are supplied to the control line circuit for controlling the traffic governing unit to its first position, half cycles of the other relative polarity of the alternating current source at the field station are passed to the control line circuit for indicating the first position of the traffic governing unit, and when half cycles of the other relative polarity of the alternating current source at the office are supplied to the control circuit for controlling the traffic governing unit to its second position, half cycles of said one relative polarity of the alternating current source at the station are supplied to the control circuit for indicating the second position of the traffic governing unit. It is to be seen therefore that by such use of the relative polarities of the half cycles of the two sources of alternating current, a traffic governing unit is continuously controlled and indicated over a

control line circuit including but one control line wire and a common line wire.

Preferably the two sources of alternating current, one at the office and one at the station, are connected to the same transmission line so that the two currents are of the same frequency and are in phase. However, my invention is not limited to the condition where the two sources of alternating current are of the same frequency and in phase, and the two sources may be independent. For example, each such current source may be a tuned alternator, there being provided one alternator at each of the two locations. In such an arrangement, the frequencies of the two independent sources of alternating current are preferably markedly different from each other.

At the office, one winding of a special two winding relay is preferably included in each sending branch circuit of the control circuit for each track switch for providing special "switch in transit" and "switch locked" indications of the switch, as well as to provide an indication of a train in the vicinity of the switch.

I shall describe one form of apparatus embodying my invention, and shall then point out the novel features thereof in claims.

The accompanying drawing is a diagrammatic view showing one form of apparatus embodying my invention when used for remote control of an interlocking having an unbalanced layout of switches and signals.

Referring to the drawing, the diagram in the upper right-hand portion of the drawing designates an interlocking comprising a crossover 3 extending between an eastbound track ET and a westbound track WT. The eastbound track ET is formed by the usual insulated rail joints with a detector track section 2T, and the westbound track WT is formed with a detector track section 4T, these two track sections 2T and 4T extending beyond the limits of the crossover as is customary in such track layout. Each track section 2T and 4T is provided with a track circuit which includes a track relay designated by the reference character R, plus a prefix corresponding to the reference character of the section, the relationship of each track relay with its section being indicated by a dash line.

In accordance with standard practice, signals R2 and L2 are located at the opposite ends of the track section 2T for governing traffic through the section, signal R2 being provided with two mechanisms R2A and R2B mounted on the same mast, and signal L2 being provided with but one mechanism. In like manner, signals L4 and R4 are located at the opposite ends of track section 4T for governing traffic through that section, signal L4 comprising two signal mechanisms L4A and L4B, and signal R4 having but one mechanism.

Additional approach signals would be provided in accordance with standard practice, but such additional signals are not shown since they are not required for a full understanding of my invention. The type of signal mechanism used is immaterial, and may be any one of the several well-known forms.

The two track switches of crossover 3 are preferably operated by power switch machines SM1 and SM2. The type of switch machines used is also immaterial and they are shown by the symbol commonly used to indicate such power switch machines. It is sufficient for the instant application to point out that each switch machine SM1 and SM2 includes a reversible

motor and a mechanism (not shown) of such nature that when the motor is supplied with current over one operating circuit the mechanism is operated as required to move the associated track switch to one extreme position, such as its normal position, and when the motor is supplied with current over a second operating circuit, the mechanism is operated as required to move the switch to its other extreme position, that is, to its reverse position. Switch machines SM₁ and SM₂ are made dependent upon each other in their operations so that the two ends of the crossover 3 agree as to position. That is, the two switches of crossover 3 are related switches capable of being controlled by the same control circuit.

It is to be pointed out that signals R₂ and L₂ constitute what is commonly referred to as a "right" and a "left" signal which are selectively governed by a single control circuit effective to establish either a right or a left control, that is, either a normal or a reverse control. It is to be further noted that signals R_{2A} and L₂ are used when the crossover 3 occupies its normal position and signal R_{2B} is used for governing traffic moving from eastbound track ET to westbound track WT when crossover 3 occupies its reverse position. Again, it is noted that signals R₄ and L₄ constitute "right" and "left" signals. Hence, signals L₂ and R₂, and signals R₄ and L₄ constitute in each case what I have termed a traffic governing unit capable of being controlled by a single control circuit. Since the two switches of crossover 3 are related switches, they also constitute a traffic governing unit capable of being controlled by a single control circuit. It follows, therefore, that this interlocking is unbalanced as to the switches and signals, there being one traffic governing unit for the switches and two traffic governing units for the signals.

It is to be understood, of course, that my invention is not limited to this one track layout of an interlocking, but such layout is used to illustrate the invention because it is sufficient to show the principle of the apparatus embodying my invention.

Control of the switches and signals of this interlocking is effected in part from a remote office DS through the medium of a remote control system utilizing apparatus located partly at the office DS and partly at a station FS which station is preferably located adjacent the interlocking. As will appear more fully hereinafter, the traffic governing unit consisting of the two switches of crossover 3 is controlled and indicated over a control line circuit including a control line wire W₁ and a common line wire CO. Likewise the traffic governing unit consisting of signals R₂ and L₂ is controlled and indicated over a control line circuit including a control line wire W₂ and the common line wire CO. Also, the traffic governing unit consisting of signals R₄ and L₄ is controlled over another control line circuit including a control line wire and the common line wire CO, but this latter circuit is not shown in order to simplify the drawing since the latter line circuit and its related apparatus would be substantially a duplication of the control circuit including line wires W₂ and CO and the apparatus associated therewith for controlling and indicating signals R₂ and L₂.

Office DS and station FS are provided each with a suitable source of alternating current and in the present embodiment of the invention, the

source of current at office DS is a transformer T₁ whose primary winding 10 is connected to a generator, not shown, through the medium of the usual transmission line, and the source of current at station FS is a transformer T₂ whose primary winding 11 is connected to the same generator through the transmission line. It follows that the alternating currents supplied by transformers T₁ and T₂ are of the same frequency and are in phase. As an aid in the understanding of the invention, I shall consider that the connections for transformers T₁ and T₂ are such that the terminals BX and CX of the secondary windings 12 and 13 of the two transformers are of corresponding relative polarity. That is to say, the terminals BX of the two transformers become positive and negative in polarity in step with each other, and likewise the terminals CX of the transformers become positive and negative in polarity in step with each other.

As a further aid in the understanding of the invention, I shall refer to the current supplied by a transformer when its terminal BX is positive in potential with respect to its terminal CX as being the positive half cycle of the alternating current; and the current supplied by a transformer when its terminal CX is positive in potential with respect to its terminal BX as being the negative half cycle of the alternating current. To put it another way, a positive sending half cycle of current is supplied by a transformer during the half cycle its terminal BX is positive in potential with respect to its terminal CX and a negative sending half cycle of current is supplied by a transformer during the half cycle its terminal CX is positive in potential with respect to its terminal BX. The manner whereby secondary windings 12 and 13 of transformers T₁ and T₂, respectively, are connected to the different control circuits for supplying current thereto will appear as the specification progresses, but it is to be observed that the CX terminal of each transformer is connected permanently to the common line wire CO, such connections including wire 30 at office DS and wire 49 at station FS.

Referring to office DS, three manually controlled means are provided, a switch lever 3L and two signal levers 2L and 4L. As will appear shortly, lever 3L is used to control crossover 3, lever 2L is used to control signals R₂ and L₂ and lever 4L to control signals R₄ and L₄. In accordance with usual practice, switch lever 3L is operable to either a normal position N or to a reverse position R, and each signal lever 2L and 4L is normally positioned at a mid position C and is operable to either a left-hand position LH or to a right-hand position RH. Four circuit controlling contacts 14, 15, 16 and 17 are operatively connected to lever 3L, as indicated by a dash line 18. These contacts, as well as other contacts operated by the other levers, are shown conventionally by a circle having placed therein a reference character indicating the position of the associated lever at which the contact is closed. For example, at a first or normal position N of lever 3L, contacts 14 and 17 are closed and at a second or reverse position R of the lever, the contacts 15 and 16 are closed. Likewise, four circuit controlling contacts 19, 20, 21 and 22 are operatively connected to lever 2L, as indicated by a dash line 23, the arrangement being such that 75 at the RH position of the lever contacts 20 and

21 are closed and at the LH position of the lever contacts 19 and 22 are closed.

In the present embodiment of my invention these manually controlled means at the office station are shown as manually operable levers, but it is to be understood that levers 3L, 2L and 4L can be replaced by manually controlled relays whose front and back contacts replace the lever contacts shown in the drawing. When manually operable levers are used, such levers may be provided with the usual mechanical locking, or they may be of the usual push button type used in an all relay type of interlocking machine. When relays are used and such relays are the relays of a route type of interlocking, contacts 14 and 16 of lever 3L could be replaced by a front and back contact of a first switch control relay of a route network, and contacts 17 and 15 could be replaced by a front and back contact of a second switch control relay of the network. Again, if desired, contacts 14 and 17 could be made two separate front contacts of the first switch control relay, and contacts 15 and 16 could be replaced by two separate front contacts of the second switch control relay. In like manner, the contacts of signal lever 2L can be replaced by contacts of manually controlled relays, and it is to be understood that my invention contemplates the use of manually controlled relays as well as manually operable levers.

At office DS, the control line circuit W1—CO used for controlling crossover 3 terminates in four branch circuits which are selectively closed by the contacts of switch lever 3L, and two of which branch circuits serve to supply current to the line circuit from the office current source and the other two of which branch circuits serve to receive current transmitted from the station current source over the associated control line circuit. The first one of the sending branch circuits can be traced from terminal BX of transformer T1 over an asymmetric unit 24, top winding 25 of a relay LRP to be later described, contact 14 of lever 3L and wire 26 to the line wire W1; and the second sending branch circuit can be traced from terminal BX over asymmetric unit 27, lower winding 28 of relay LRP, lever contact 15 and wire 26 to line wire W1. Asymmetric units 24 and 27 are disposed reverse to each other and as here shown, asymmetric unit 24 is disposed to permit the positive half cycles of the alternating current of transformer T1 to pass to line wire W1 over the first sending branch circuit when lever 3L is at its normal position to close contact 14, and asymmetric unit 27 is disposed to permit the negative half cycles of the alternating current to pass over the second sending branch circuit when the lever 3L is moved to its reverse position R to close contact 15. Of the two receiving branch circuits, the first one can be traced from line wire W1 over wire 26, lever contact 17, winding of an indication relay 3NK, to be referred to later, and an asymmetric unit 29 to wire 30 which is connected to the common line wire CO. The second receiving branch circuit involves wire 26, lever contact 16, winding of an indication relay 3RK, an asymmetric unit 31 and wire 30. The asymmetric units 29 and 31 are disposed reverse to each other and are further so disposed that when lever 3L is at its normal position to close the first sending branch circuit for supplying the positive half cycles of the alternating current from transformer T1 to the line circuit, the receiving branch circuit connected to the line circuit by lever contact 17 in-

cludes asymmetric unit 29 which is disposed to block the flow of such positive half cycles of current; and at the reverse position of lever 3L when the second sending branch circuit is closed for supplying negative half cycles of the alternating current from transformer T1 to the line circuit, the second receiving branch circuit connected to the line circuit at contact 16 of the lever includes asymmetric unit 31 disposed to block the flow of such negative half cycles of current. In other words, the arrangement of the asymmetric units and the selection effected by the contacts of lever 3L are such that neither one of the receiving branch circuits associated with the control line circuit W1—CO can be energized by current supplied from the office transformer T1.

The indication relays 3NK and 3RK are magnetically biased relays which are picked up by current of one relative polarity only. For example, these relays as well as other magnetically biased relays to be referred to later may be of the type covered by the United States Letters Patent No. 2,203,888, granted June 11, 1940, to H. E. Ashworth for Electrical relay. Looking at relay 3NK, this relay is picked up by current flowing in the direction indicated by the arrow placed on the relay and which direction corresponds to the forward direction for the asymmetric unit 29 included in the same receiving branch circuit. The contact member 32 of relay 3NK is biased both magnetically and by gravity to engage its back contact when the relay is deenergized, is held in the released position in case the relay is energized by current flowing in the direction opposite to that indicated by the arrow on the relay and is picked up to engage a front contact when the relay is energized by current flowing in the direction corresponding to that indicated by the associated arrow. In like manner, contact member 33 of relay 3RK is biased to the released position to engage a back contact when the relay is deenergized, is held in that position in case the relay is energized by current flowing in the relay winding in the direction reverse to that indicated by the arrow placed on the relay and is picked up to engage a front contact when the relay is energized by current flowing in the relay winding in the direction indicated by the associated arrow. The function of relays 3NK and 3RK as well as that of relay LRP, will appear when the operation of the apparatus is described.

The control line circuit W2—CO also terminates in four branch circuits at the office DS and which branch circuits are selectively closed by contacts of the signal lever 2L, and two of which branch circuits are used for sending control current from the office station current source, and the other two of which are used to receive indication current supplied to the line circuit from the station current source. A first sending branch circuit for control circuit W2—CO includes terminal BX of transformer T1, wire 34, asymmetric unit 35, contact 19 of lever 2L and wire 36 connected to the control line wire W2; and the second sending branch circuit involves terminal BX of transformer T1, wire 34, asymmetric unit 37, lever contact 20 and wire 36. Asymmetric units 35 and 37 are disposed reverse to each other, unit 35 being disposed to pass the positive half cycles of the alternating current supplied by transformer T1 and unit 37 being disposed to pass the negative half cycles of the alternating current. Thus at the left-hand position LH of lever 2L, contact 19 is closed and con-

trol current consisting of the positive half cycles of alternating current is supplied to the control line circuit W2—CO, and at the right-hand position RH of lever 2L contact 20 is closed and control current consisting of the negative half cycles of the alternating current is supplied to the line circuit. A first one of the associated receiving branch circuits includes wire 36 connected to line wire W2, lever contact 22, winding of an indication relay 2LK, asymmetric unit 38, and wires 39 and 30 connected to the common line wire CO. The second associated receiving branch circuit involves wire 36, lever contact 21, winding of an indication relay 2RK, asymmetric unit 40 and wires 39 and 30. Asymmetric units 38 and 40 are disposed reverse to each other and the arrangement is further such that when lever 2L is set at its LH position closing contacts 19 and 22 and positive half cycles of current from transformer T1 are supplied to the control line circuit such current is blocked by asymmetric unit 38 of the closed receiving branch circuit; and when lever 2L is set at its RH position closing contacts 20 and 21 and negative half cycles of alternating current are passed from transformer T1 to the control line circuit, such current is blocked by asymmetric unit 40 of the closed receiving branch circuit. The indication relays 2LK and 2RK are magnetically biased neutral relays of the same type as the relays 3NK and 3RK and their description need not be repeated except to point out that contact member 41 of relay 2LK is picked up only when relay 2LK is energized by current flowing in the relay in the direction indicated by an arrow placed on the relay, and contact member 42 of relay 2RK is picked up only when that relay is energized by current flowing in the direction of the arrow placed on that relay. Also, it is to be observed that each relay 2LK and 2RK is picked up by current of the polarity passed by the asymmetric unit of the same receiving branch circuit. The function of relays 2LK and 2RK will also be taken up when the operation of the apparatus is described.

As stated hereinbefore, the apparatus and circuits associated with signal lever 4L for controlling signals L4 and R4 are not shown for the sake of simplicity since they are but a duplication of those associated with signal lever 2L for controlling signals L2 and R2.

Referring now to station FS, the control line circuit W1—CO terminates in four branch circuits, two of which are used for receiving and two for sending. A first receiving branch circuit includes wire 43 connected to line wire W1, front contacts 44 and 45 of track relays 4TR and 2TR, respectively, back contact of contact member 46 of a reverse switch controlling relay 3RWR to be referred to later, winding of a normal switch controlling relay 3NWR also to be referred to later, asymmetric unit 47, front contact 48 of a relay LR to be referred to later, and wire 49 connected both to the common line wire CO and to the terminal CX of transformer T2. The second receiving branch circuit includes wire 43, front contacts 44 and 45, back contact of contact member 50 of relay 3NWR, winding of relay 3RWR, asymmetric unit 51, front contact 48 of relay LR and wire 49. Starting at terminal BX of transformer T2, a first one of the sending branch circuits associated with control line circuit W1—CO, includes wire 52, asymmetric unit 53, front contact 54 of a normal switch repeater relay 3NWP to be referred to later, front contact of contact member 55 of relay 3NWR, front

contacts 45 and 44 of track relays 2TR and 4TR, respectively, and wire 43 connected to line wire W1; and a second sending branch circuit extends from terminal BX over wire 52, asymmetric unit 56, front contact 57 of a reverse switch repeater relay 3RWP, front contact of contact member 46 of relay 3RWR, front contacts 45 and 44 and wire 43 to line wire W1. In these station branch circuits for the control line circuit W1—CO, it is to be noted that in the receiving branch circuits asymmetric units 47 and 51 are disposed reverse from each other, switch controlling relays 3NWR and 3RWR, which are biased neutral relays of the type hereinbefore described, are each interposed in the respective receiving branch circuit to be picked up by current of the polarity passed by the asymmetric unit of the same circuit and that these two receiving branch circuits are interlocked by each being controlled over a back contact of the relay of the other receiving branch circuit. Regarding the two associated sending branch circuits, the two asymmetric units 53 and 56 thereof are disposed reverse to each other, the two branch circuits are selectively closed over front contacts of the two switch repeater relays 3NWP and 3RWP, which are in turn controlled according to the position of the crossover 3 as will shortly be described, and are controlled over front contacts of the switch controlling relays 3NWR and 3RWR. Also the arrangement is such that when the first receiving branch circuit effective to pass positive half cycles of current from transformer T1 is closed, the first sending branch circuit effective to pass the negative half cycles of the current of transformer T2 is closed, and when the second receiving circuit effective to pass the negative half cycles of current from transformer T1 is closed, the second sending circuit effective to pass the positive half cycles of the current of transformer T2 is closed. Consequently at the field station neither one of receiving branch circuits of the control line circuit W1—CO can be energized by current supplied from the station current source. Furthermore, the branch circuits are all governed over contacts of the two track relays 2TR and 4TR of the detector track sections associated with cross-over 3, and are further governed over a front contact 48 of a locking relay LR, relay LR being controlled by the approach, route and detector locking usually provided at such interlocking but which are not shown since such locking forms no part of my present invention and would be in accordance with standard practice.

Switch controlling relays 3NWR and 3RWR govern the operating circuits for switch machines SM1 and SM2 for operating the crossover. When normal switch controlling relay 3NWR is picked up to close front contact 59, a normal operating circuit is formed which includes terminal B1 of a suitable source of current, such as a battery not shown, front contact 59, wire 60, switch machine SM1 and wire 62 to terminal C1 of the same source of current, and switch machine SM1 is operated as required to move the associated track switch to its corresponding normal position. This operating circuit is extended from switch machine SM1, over wire 63, through switch machine SM2 and wire 64 to terminal C1 of the current source, and switch machine SM2 is operated as required to move the corresponding end of the crossover to its normal position. When reverse switch controlling relay 3RWR is picked up to close front contact 65, a reverse

operating circuit is formed which includes terminal B1, front contact 65, wire 66, switch machine SM1 and wire 62 to terminal C1, and switch machine SM1 is operated as required to move the corresponding end of the crossover to its reverse position. This reverse operating circuit is extended from switch machine SM1 over wire 67, through switch machine SM2 and wire 64 to terminal C1, and switch machine SM2 is operated as required to move its corresponding end of the crossover to the reverse position.

Switch repeater relays 3NWP and 3RWP are governed by the position of crossover 3 in any one of the several well-known ways, and as here shown relay 3NWP is provided with a circuit including terminal B1, a contact 68 of a switch circuit controller operably connected to the switch at the west end of the crossover and moved to the position illustrated by the solid lines in the drawing when the respective switch is at its normal position, contact 69 of a switch circuit controller operably connected to the switch at the east end of the crossover and moved to the position illustrated by the solid lines at the normal position of the respective switch, winding of relay 3NWP and terminal C1. When the switches of crossover 3 are both at their reverse positions causing contact members 68 and 69 to be moved to the positions illustrated by the dotted lines in the drawing, a circuit is formed for relay 3RWP, as will be readily understood by an inspection of the drawing. It follows that relay 3NWP is picked up only when both ends of the crossover occupy their respective normal positions, and relay 3RWP is picked up only when both ends of the crossover occupy their respective reverse positions. As explained hereinbefore, relays 3NWP and 3RWP control the sending branch circuits of the control line circuit W1—CO.

Referring to the control line circuit W2—CO, this circuit also terminates in four branch circuits at the station FS, two of which are used for receiving current and two of which are used for sending current. A first receiving circuit includes wire 70 connected to line wire W2, back contact of contact member 71 of a signal controlling relay RHR, winding of a signal controlling relay LHR, asymmetric unit 72 and wire 49 connected to common line wire CO. The second receiving branch circuit includes wire 70, back contact of contact member 73 of relay LHR, winding of relay RHR, asymmetric unit 74 and wire 49. A first sending branch circuit can be traced from terminal BX of transformer T2 over wire 52, asymmetric unit 75, front contact 76 of a signal repeater relay LHP, front contact of contact member 73 of relay LHR and wire 70 to line wire W2. The second sending branch circuit includes terminal BX of transformer T2, wire 52, asymmetric unit 77, front contact 78 of a signal repeater relay RHP, front contact of contact member 71 of relay RHR and wire 70 connected to line wire W2. It is to be seen that of the receiving branch circuits at station FS associated with the control circuit W2—CO, the first one is effective to pass the positive half cycles of current of transformer T1 and the second is effective to pass the negative half cycles of current of transformer T1, and that each of the signal controlling relays LHR and RHR is effectively energized and picked up by current of the polarity passed by the associated asymmetric unit of the same branch circuit, relays LHR and RHR being magnetically biased neutral relays of the type previously described, and each being picked up when ener-

gized by current flowing in the relay in the direction of an arrow placed on the relay. Also the two receiving branch circuits are interlocked by each including a back contact of the relay of the other circuit. In the sending branch circuits the asymmetric units 75 and 77 are disposed reverse to each other, and the two sending branch circuits are selectively governed by the signal repeater relays LHP and RHP and are also governed by the signal controlling relays LHR and RHR. Furthermore, it is to be observed that the receiving branch circuits for the control circuit W2—CO are not energized by current supplied by the station transformer T2.

The signal controlling relays LHR and RHR govern the operating circuits of signals R2 and L2 through the medium of signal control relays, there being one signal control relay for each of the signals. To be explicit, when relay LHR is picked up a circuit is formed from terminal B1 over front contact 79 of relay LHR, winding of a signal control relay L2H for signal L2, contacts 80 and 81 of the switch circuit controllers for the crossover 3 and closed at the normal position of the crossover, and terminal C1 of the current source, and relay L2H is picked up. As shown in the upper right-hand portion of the drawing signal control relay L2H when picked up to close front contact 83, completes a simple operating circuit for signal L2 and that signal is operated as required to display a proceed indication. Furthermore, when signal control relay L2H is picked up to operate signal L2, signal repeater relay LHP is energized over an obvious circuit including front contact 84 of relay L2H. It is to be recalled that signal repeater relay LHP controls at its front contact 76 the first sending branch circuit for the associated control circuit W2—CO. Consequently, when a control current consisting of positive half cycles of current of transformer T1 is received at station FS, over the line circuit W2—CO, the signal controlling relay LHR is picked up to cause energization of signal control relay L2H and that relay in turn controls the operating circuit of signal L2 and the energizing circuit for the signal repeater relay LHP which latter relay closes the sending branch circuit for supplying indication current consisting of negative half cycles of current from transformer T2 to the associated control circuit W2—CO.

Again when signal controlling relay RHR is picked up, a circuit is formed for energizing signal control relays R2AH and R2BH, one or the other of the relays being energized according to the position of crossover 3. The circuit includes terminal B1, front contact 85 of relay RHR, winding of relay R2AH, contacts 86 and 87 of the switch circuit controllers for the crossover closed at the normal position of the crossover, and terminal C1. In case crossover 3 is moved to its reverse position so that contact members 86 and 87 are moved to the positions illustrated by the dotted lines in the drawing, then this circuit controlled by relay RHR is completed through winding of signal control relay R2BH, and contacts 86 and 89 to terminal C1. As shown adjacent signal R2, signal control relay R2AH when picked up completes at its front contact 88 an obvious operating circuit for signal R2A and that signal is operated as required to display a proceed indication; and signal control relay R2BH when picked up completes at its front contact 89 an obvious operating circuit for signal R2B, and that signal is operated as required to display a proceed indication.

When either relay R2AH is picked up to close front contact 91, or relay R2BH is picked up to close front contact 92, signal repeater relay RHP is energized and picked up to control at its front contact 78 the second sending branch circuit for the control circuit W2—CO. Consequently, when a control current consisting of the negative half cycles of current from transformer T1 is received from the control line circuit W2—CO at station FS, signal controlling relay RHR is picked up to control relay R2AH or R2BH depending upon the position of the crossover, and these relays in turn cause operation of signal R2A or R2B and energization of signal repeater relay RHP, which latter relay then controls the corresponding sending branch circuit. The signal control relays L2H, R2AH and R2BH would, of course, be controlled by traffic conditions but such traffic control is not shown since it forms no part of my invention and would be in accordance with usual practice.

In describing the operation of the apparatus I shall first assume that the switch lever 3L is set in its normal position N and signal levers 2L and 4L are set in their mid positions C. Lever contacts 14 and 17 are closed in the normal position N of lever 3L and consequently each half cycle that terminal ZX of transformer T1 is of positive relative polarity current flows through the sending branch circuit comprising asymmetric unit 24, winding 25 of relay LRP and contact 14, thence over line wire W1 to station FS, through the station receiving branch circuit including normal switch controlling relay 3NWR and asymmetric unit 47 to line wire CO and back over the common line wire CO to terminal CX of transformer T1. Relay 3NWR is effectively energized and picked up by such control current comprising the positive half cycles of the current from transformer T1 and relay 3NWR in picking up causes operation of crossover 3 to its normal position in the manner previously described. Switch repeater relay 3NWP is effectively energized in response to the normal position of the crossover to close the station sending branch circuit including asymmetric unit 53 so that each half cycle that terminal CX of transformer T2 is of positive relative polarity current flows over the common line wire CO to the office DS, through the office receiving branch circuit comprising asymmetric unit 29, indication relay 3NK, lever contact 17 and wire 26 to line wire W1, back to station FS and through the sending branch circuit including front contact of contact member 50 of relay 3NWR, front contact 54 of relay 3NWP, asymmetric unit 53 and to terminal BX of transformer T2. Such indication current comprising the negative half cycles of the current from transformer T2 causes relay 3NK to be picked up, and relay 3NK on picking up to close the front contact of its contact member 32 completes a local indication circuit easily traced for a normal switch indication lamp 3N and that lamp is illuminated to indicate the normal position of crossover 3. It is to be seen therefore that crossover 3 is continuously controlled and indicated over the control circuit including line wires W1 and CO, the control current consisting of the positive half cycles of the alternating current supplied by transformer T1 at the office and the indication current consisting of the negative half cycles of the alternating current as supplied by the transformer T2 at the station. It is to be noted that the relay LRP at the office station is energized and picked up by

such control current but operation of relay LRP at this time performs no particular function.

I shall next describe the operation that follows the moving of lever 3L to its reverse position R to control crossover 3 to its reverse position. At the reverse position R of lever 3L, contacts 14 and 17 are opened and contacts 15 and 16 are closed. The opening of contact 14 causes normal switch controlling relay 3NWP to be deenergized. The closing of contact 15 causes a control current consisting of negative half cycles of current from transformer T1 to flow over the common line wire CO to station FS, through the station receiving branch circuit including asymmetric unit 51 and reverse switch controlling relay 3RWR, thence back over line wire W1 to the office through the office sending branch circuit comprising lever contact 15, lower winding 28 of relay LRP and asymmetric unit 27 and to terminal BX of transformer T1. This control current consisting of negative half cycles of current supplied by transformer T1 causes the switch controlling relay 3RWR to be picked up and the reverse operating circuit for crossover 3 to be closed so that crossover 3 is operated to its reverse position. At the reverse position of crossover 3 switch repeater relay 3RWP is picked up to close the corresponding station sending branch circuit so that the positive half cycles of current from transformer T2 flow through the sending branch circuit including asymmetric unit 56 and front contact 57 of relay 3RWP, thence over line wire W1 to the office, through the office receiving branch circuit comprising contact 16, relay 3RK and asymmetric unit 31, and back over the common line wire CO to terminal CX of transformer T2. Relay 3RK is picked up by this indication current consisting of the positive half cycles of the current from transformer T2, and relay 3RK completes at the front contact of its contact member 33 an indication circuit for indication lamp 3R, and that lamp is illuminated to indicate the reverse position of the crossover.

It is to be noted that while the switches of crossover 3 are in transit from the normal to the reverse position, both switch repeater relays 3NWP and 3RWP are released and no indication current is received at the office, with the result both indication relays 3NK and 3RK are released. Relay LRP however is energized and picked up by the control current and a local indication circuit is formed from terminal BX of transformer T1 over back contacts of the contact members 32 and 33 of relays 3NK and 3RK, respectively, front contact 94 of relay LRP, lamp IT and to terminal CX, and lamp IT is illuminated to provide a "switch in transit" indication. Furthermore, it is to be pointed out that in case either detector section 2T or 4T is occupied so as to cause the release of track relay 2TR or 4TR, the crossover 3 is electrically locked against movement because the control circuit W1—CO is held open at the station. With circuit W1—CO held open at the station, both the control and indication currents are interrupted with the result that all the relays LRP, 3RK and 3NK are released. Under this condition of the relays associated with lever 3L, a circuit is formed including the back contacts of contact members 32 and 33, back contact 95 of relay LRP and lamp OS, and lamp OS is illuminated to indicate the presence of a train in one or both of the detector track sections. Also a circuit is formed for a lamp LO at back contact 93 of relay LRP to provide a special "switch locked" indication.

Again under traffic conditions that would cause relay LR at the station to be deenergized to open its front contact 43, the station receiving branch circuits are open to electrically lock crossover 3 against operation. Relay LRP is now deenergized closing its back contact 33 to cause lamp LO to be illuminated as explained above to indicate the "switch locked" condition. When relay LR is thus released causing both switch controlling relays 3NWR and 3RWR to be released, the associated sending branch circuits are held open at the station with the result that no indication current is supplied and both indication relays 3NK and 3RK are released with the result that the lamp OS is also illuminated when relay LR is released to provide an indication of the presence of a train in the vicinity of the crossover 3.

The operation following a movement of lever 3L from its reverse position R to its normal position N to effect a movement of the crossover 3 from its reverse to its normal position is similar to that following the movement of lever 3L to its reverse position and such operation of the apparatus to move the crossover back to its normal position will be readily understood by an inspection of the drawing taken in connection with the description of the operation of the apparatus to move the crossover to its reverse position.

At the mid position C of signal lever 2L, the 30 respective lever contacts are all open and consequently the control line circuit W2—CO is deenergized. Under such deenergized condition of the control circuit W2—CO, both indication relays 2RK and 2LK are released and a local indication circuit is formed from terminal BX of transformer T1 over back contacts of the contact members 42 and 41 of relays 2RK and 2LK, respectively, lamp 2S and to terminal CX, and lamp 2S is illuminated as a stop position indication for the signals controlled by lever 2L.

I shall next assume that with switch lever 3L set at its normal position to effect the normal position of crossover 3, the signal lever 2L is moved to its left-hand position LH to control signal L2. At the LH position of lever 2L, contacts 19 and 22 are closed and each cycle that terminal BX of transformer T1 is of positive relative polarity, current flows through the office sending branch circuit comprising asymmetric unit 35 and contact 19, line wire W2, through the station receiving branch circuit comprising signal controlling relay LHR and asymmetric unit 72 to the common line wire CO and back to terminal CX of transformer T1. Relay LHR is picked up by such control current consisting of the positive half cycles of the current supplied by transformer T1. Relay LHR on picking up controls relay L2H to cause operation of signal L2 and energization of signal repeater relay LHP in the manner described hereinbefore. Relay LHP when picked up to close its front contact 76 completes the station sending branch circuit and each half cycle that terminal CX of transformer T2 is of positive relative polarity, indication current flows over the common line wire CO, through the office receiving branch circuit comprising asymmetric unit 38, indication relay 2LK and lever contact 22, and thence over the line wire W2 and the station sending branch circuit comprising front contact of the contact member 73 of relay LHR, front contact 76 of relay LHP and asymmetric unit 75 to the terminal BX of transformer T2. Relay 2LK is energized and picked up by this indication current consisting 75

of the negative half cycles of the current supplied from transformer T2, and relay 2LK on picking up to close the front contact of its contact member 41 completes a local circuit for indication lamp L2S and that lamp is illuminated to indicate that signal L2 is controlled to its proceed position. It follows that signal L2 is continuously controlled and indicated over the line circuit W2—CO in response to signal lever 2L moved to its LH position, the control current consisting of the positive half cycles of the alternating current from transformer T1 and the indication current consisting of the negative half cycles of the alternating current from transformer T2.

In the event signal lever 2L is moved to its RH position when crossover 3 is normal, the closing of contacts 20 and 21 of lever 2L controls signal R2A to its proceed position. During each half cycle that terminal CX of transformer T1 is of positive relative polarity, current flows over the common line wire CO to the station, through the receiving branch circuit comprising asymmetric unit 74 and signal controlling relay RHR, back over line wire W2 to the office and through the sending branch circuit comprising contact 20 and asymmetric unit 37 to terminal BX of transformer T1. Relay RHR is effectively energized and picked up by this control current consisting of the negative half cycles of the current supplied from transformer T1, and relay RHR on picking up closes front contact 65 to control relay R2AH and that relay in turn causes signal R2A to be operated to a proceed position, 35 and signal repeater relay RHP to be energized. Relay RHP when picked up closes front contact 78, closing the corresponding station sending branch circuit so that each half cycle that terminal BX of transformer T2 is of positive relative polarity, current flows through the sending branch circuit comprising asymmetric unit 77 and front contact 78 of relay RHP, over the line wire W2 to the office, through the office receiving branch circuit comprising contact 21, relay 2RK and asymmetric unit 40, and thence over the common line wire CO to terminal CX of transformer T2. Relay 2RK is picked up by such indication current consisting of the positive half cycles of the current supplied by transformer T2, and relay 2RK on picking up to close the front contact of its contact member 42, completes a local indication circuit for lamp R2S and that lamp is illuminated to indicate that signal R2A is controlled to its proceed position. In the event crossover 3 is at its reverse position when signal lever 2L is moved to its RH position the relay R2BH is selected and signal R2B is controlled to a proceed position in response to the picking up of relay RHR and this position of signal R2B is indicated by the illumination of lamp R2S in the manner explained above in connection with the operation of signal R2A.

It follows that signal R2A or R2B as the case may be is continuously controlled and indicated over the control circuit W2—CO when lever 2L is moved to its RH position, the control current consisting of negative half cycles of the alternating current from transformer T1 and indication current consisting of positive half cycles of alternating current from transformer T2.

As stated hereinbefore, the signals L4 and R4 are controlled and indicated by signal lever 4L and an associated control circuit in the same manner as signals L2 and R2 are controlled by

signal lever 2L and the associated control circuit W2—CO.

Advantages of a remote control system embodying my invention include the continuous control and indication of a traffic governing unit over a single line circuit and which control and indication is accomplished without critical time values in the operation of the respective apparatus. Also extra circuits and apparatus are not required because of an unbalanced condition of an interlocking layout. Manual control can be effected by levers or by relays. Special "switch in transit" and "switch locked" indications are provided for a switch as well as an indication of a train in the vicinity of the switch. Use of magnetically biased neutral relays provides additional assurance that a control relay is not inadvertently energized and picked up by current of the reverse polarity. It is to be pointed out that in using biased neutral relays of the type here described, the asymmetric units in certain of the branch circuits may be omitted if desired and proper selection effected by the biased relays alone.

Although I have herein shown and described but one form of remote control system embodying my invention, it is understood that various changes and modifications may be made therein within the scope of the appended claims without departing from the spirit and scope of my invention.

Having thus described my invention, what I claim is:

1. A remote control system for railways comprising, an office provided with a manually controlled means and an indication means each operable to a first and a second condition, a station provided with a traffic governing unit operable to a first and a second position, a source of alternating current at the office and at the station, a control line circuit extending between said office and station and terminating in two sending and two receiving branch circuits at each such location, said sending branch circuits at each location interposed between the current source and said line circuit and effective when closed, one to pass the positive half cycles of current only and the other to pass the negative half cycles of current only of the associated current source, said receiving branch circuits at each location connected to said line circuit and each including a relay characterized by being operated by current of one polarity only and the two relays at a location being arranged for operation by currents of opposite polarities, means including contacts of the station relays to operate said traffic governing unit to its first or second position according to which relay is operated, means including contacts of the office relays to operate said indication means to its first or second condition according to which relay is operated, means including contacts governed by said manually controlled means to selectively close the office sending and receiving branch circuits to send positive half cycles and effectively receive only negative half cycles of alternating current at said first condition of the manually controlled means and to send negative half cycles and effectively receive only positive half cycles of alternating current at said second condition of the manually controlled means, and means including contacts governed by said traffic governing unit to selectively close the station sending branch circuits to send negative half cycles of current when positive half cycles of current are received and to send positive half cycles of negative half cycles are received.

2. A remote control system for railways, comprising an office provided with a manually controlled means and an indicating means each operable to a first and a second condition, a station provided with a traffic governing unit operable to a first and a second position, a source of alternating current at the office and at the station, a control line circuit extending between said office and station and terminating in two sending and two receiving branch circuits at each such location, said sending branch circuits at each

15 such location interposed between the current source and said line circuit and effective when closed one to pass the positive half cycles of current only and the other to pass the negative half cycles of current only of the associated current source, said receiving branch circuits at each location connected to said line circuit and each including a relay characterized by being operated by current of one polarity only and the two relays at a location being arranged for operation by currents of opposite polarities, means including contacts of the station relays to operate said traffic governing unit to its first or second position according to which relay is operated, means including contacts of the office relays to operate said indication means to its first or second condition according to which relay is operated, means including contacts governed by said manually controlled means to selectively close the office sending and receiving branch circuits to send positive half cycles and effectively receive only negative half cycles of alternating current at said first condition of the manually controlled means and to send negative half cycles and effectively receive only positive half cycles of alternating current at said second condition of the manually controlled means, means including contacts of said relays at the station to interlock the station receiving branch circuits and permit only one relay to be operated at a time, and means including contacts governed by said traffic governing unit to selectively close the station sending branch circuits to send negative half cycles of current when positive half cycles of current are received and to send positive half cycles when negative half cycles are received.

3. A remote control system for railways comprising, an office having a manually controlled means and an indicating means each operable to a first and a second condition, a station having a traffic governing unit operable to a first and a second position, a source of alternating current at said office and at said station, a control line circuit including a pair of line wires extending between said office and station, two sending branch circuits at each such location one effective to pass only the positive half cycles and the other effective to pass only the negative half cycles of alternating current, two receiving branch circuits at each such location each including a biased relay characterized by being picked up by current of one polarity only, means including contacts of the station receiving branch circuit relays to operate said traffic governing unit to its first or second position according to which relay is picked up, means including contacts of the office receiving branch circuit relays to operate the indicating means to its first or second condition according to which relay is picked up, means including contacts governed by said manually controlled

means to selectively connect the office current source to said line circuit through the office sending branch circuits according to the first and second condition of the manually controlled means and to selectively connect the office receiving branch circuits across the control circuit according to the first and second condition of the manually controlled means, and means including contacts governed by the traffic governing unit to selectively connect the station current source to the control circuit through the station sending branch circuits according to the first or second position of the traffic governing unit.

4. In apparatus for use in a remote control system for railways including an office provided with a manually controlled means and an indicating means each operable to a first and a second condition, a station having a traffic governing unit operable to a first and a second position, a source of alternating current at said office and at said station and a line circuit extending between such locations and terminating at each location into two sending and two receiving branch circuits of which the sending branch circuits at each location have interposed therein asymmetric units so that one passes the positive half cycles only and

the other the negative half cycles only of the source of the same location, the combination comprising, magnetically biased relays characterized by being picked up by current of one polarity only interposed one in each of said receiving branch circuits, said two relays at each location arranged to be picked up by currents of opposite polarities, means including contacts of the station relays to operate the traffic governing unit to its first and second position according to the relay picked up, means including contacts of the office relays to operate the indicating means to the first or second condition according to the relay picked up, means including contacts of said manually controlled means to selectively connect said office current source to said line circuit through the office sending branch circuits and to selectively connect the office receiving branch circuits across the line circuit, means including contacts governed by the traffic governing unit and contacts governed by the station relays to selectively connect the station current source to the line circuit through the field station sending branch circuits, and means to connect the station receiving branch circuits across the line circuit.

PAUL H. CRAGO.
